UNITED STATES PATENT OFFICE.

CLARENCE M. HOLLEY, OF DETROIT, MICHIGAN, ASSIGNOR TO UTILITY COMPRESSOR COMPANY, OF DETROIT, MICHIGAN, A CORPORATION OF MICHIGAN.

ARTIFICIAL REFRIGERATING UNIT.

Application filed December 31, 1917. Serial No. 209,687.

To all whom it may concern:

Be it known that I, CLARENCE M. HOLLEY, a citizen of the United States, residing at Detroit, county of Wayne, State of Michigan, have invented a certain new and useful Improvement in Artificial Refrigerating Units, and declare the following to be a full, clear, and exact description of the same, such as will enable others skilled in the art to 10 which it pertains to make and use the same, reference being had to the accompanying drawings, which form a part of this specification.

The principal object of the invention is to 15 provide artificial refrigerating apparatus adaptable for attachment as a unit to a refrigerator box whereby any ordinary refrigerator box may be made a complete artificial refrigerator by mounting the unit 20 thereon, provision being made for a circulation of air between the storage compartment and the unit.

While a particular design of refrigerating apparatus is here shown and described, 25 it is to be understood that any well known type of artificial refrigerating apparatus may be utilized.

The construction of the unit and the several component parts thereof in relationship 30 with the box is shown in the drawing which is a vertical section of a portion of a refrigerator and of the refrigerating unit mounted thereon.

The refrigerator proper is shown at 1 and 35 provided with a central dividing wall 2 forming storage compartments 3 and 4. The usual refrigerators now in use are provided with a vertical wall similar to the wall 2 between the ice compartment usually positioned at 3 and the storage compartment 4, and this wall in such former types of refrigerators did not extend to the upper cover 5 of the refrigerator. With the construction here shown, however, this wall 2 extends 40 upward, and preferably through an aperture 6 provided in the cover member 5, terminating flush with the upper surface thereof as indicated in the drawing.

The artificial refrigerating unit is mounted 50 in a box 7 adapted to be placed on top of the refrigerator cover 5 as indicated. This box is provided with a compartment 8 in which the cooling coils 9 are positioned, and the compartment 8 is insulated by means 55 of cork or other filling as indicated at 10.

The compartment 8 is separate from the balance of the box 7 as indicated providing a compartment 11 in which the operating apparatus is mounted including the motor 12 and a compressor 13 operated by the motor which compresses the gas for use in the expansion coils 9. The gas is compressed and passes by means of a pipe 14 into the cooling box 15 in which water is circulated by means of the pipes 16 and 17 and in 60 which the gas is condensed to liquid form. The liquid passes from the coils in the box 15 into the expansion coils by means of a pipe 18 leading into the lower part 19 of the coil 9 which, in the construction here 65 shown, is mounted in a box having a central aperture 20. The coils in the portion 19, however, are connected with the coils 9. By this arrangement the coldest portion of the cooling coils is in the lower part 19 thereof 70 and the aperture 20 is provided to allow insertion of a tray containing water that may be frozen in small pans or the like for table use. After the refrigerant has been expanded in the coils 9 it is returned to the compressor 13 and again compressed and discharged through the pipe 14 as will be 75 readily understood.

The compartment 8 in which the coils are located is provided with the angularly positioned partition wall 21 and the opening in the bottom of the chamber 8 is of the same size as the opening 6 and the portion 6^a thereof on the opposite of the partition wall 2 of the refrigerator. By reason of the coldness of the coils 9, air in the compartment tends to fall from the coils 9 into the compartment 3 of the refrigerator. The partition wall 2 does not extend entirely to the bottom of the refrigerator, it being spaced 80 therefrom (although not here shown), and the air falling in the compartment 3 tends to force the warmer air of the compartment 4 up through the portion 6^a of the aperture in the cover 5 into the chamber 8, the angularly positioned wall forcing the same over 85 into the coils 9 where it is cooled and again falls into the chamber 3. Thus a continuous circulation of air through the refrigerating coils and storage compartment is produced 90 and with proper thermostatic control the desired temperature is continuously maintained in the storage compartment.

By this arrangement here described, the entire refrigerating apparatus may be as- 95

sembled and charged and shipped to remote points for use in conjunction with boxes of various characters, the only provision necessary being the formation of the apertures 6 and 6^a in the box and extension of the partition wall 2 therein after the manner indicated in the drawing. The box thus equipped utilizes what is ordinarily the ice compartment for the storage of food and 10 the capacity of the box is increased to such extent.

By this arrangement also, if necessity for repair of the apparatus arises, the entire unit may be removed from the box and 15 shipped to the factory for repair during which interval the compartment 3 may be used for ice. For this reason I prefer to make the partition wall 2 in two parts being provided with an upper portion, 2^a that 20 may be made removable to provide for air circulation between the compartments 3 and 4 when ice is used in the compartment 3 and the unit removed from the box. If the unit be removed it is necessary to cover the 25 apertures 6 and 6^a in some manner to prevent an escape of air from the box and introduction of the warm air from the exterior. While I have here shown a peculiar form of refrigerating coil, the coil may be 30 in any approved form adaptable for the purpose the essential characteristic being that the coil should be entirely supported by the compartment 8 of the box 7.

Having thus briefly described my invention, its utility and mode of operation, what 35 I claim and desire to secure by Letters Patent of the United States is—

1. The combination with a refrigerator box having two storage compartments and a 40 vertical partition wall therebetween and an aperture in the upper horizontal wall of the refrigerator opening into both storage compartments, of an artificial refrigerating apparatus including expansion coils, a compartment for the coils open on the lower side adapted to fit over the aperture in the refrigerator wall with the coils positioned 45 over one of the said storage compartments providing for circulation of air upward from one of the storage compartments into the coil compartment and thence downward 50 into the other storage compartment.

2. The combination with a refrigerator having two storage compartments and a vertical partition wall therebetween and an aperture in the upper horizontal wall of the refrigerator to which the partition extends, the compartments being in communication at the bottom, of an artificial refrigerating apparatus including the expansion coils and means for compressing fluid for expansion therein, a box for the said refrigerating apparatus, a compartment formed in the said box for the expansion coils, said 65 compartment having an opening in the lower

face and the box being adapted for securing to the upper wall of the refrigerator with said opening in the coil compartment in registration with the aperture in the refrigerator wall.

3. In combination a refrigerator box having two storage compartments and a vertical partition wall therebetween, the upper wall of the refrigerator box having an aperture and the partition wall extending thereinto, an artificial refrigerating apparatus including the expansion coils, a box containing the apparatus, a compartment formed in the box for the expansion coils, the coil compartment having an angularly positioned 70 wall and being open at the bottom, said apparatus and box therefor being adapted to be placed on the upper wall of the refrigerator box with the open end of the coil compartment in registration with the said aperture in the upper horizontal wall, the angularly positioned wall of the coil compartment extending over said aperture whereby atmosphere rising through one part of the aperture strikes said angular wall and is 75 deflected into the expansion coils to fall by gravity into the storage compartment therebelow.

4. The combination with a refrigerator having two storage compartments and an aperture in the upper horizontal wall opening into the top of both storage compartments of a refrigerating unit comprising a box like member having a closed compartment for the motor, compressor, etc., 80 and a separate compartment for the expansion coils, the said expansion coil compartment having an opening adapted to register with the opening in the upper horizontal wall of the refrigerator, the arrangement being such that the said expansion coils are positioned directly over one storage compartment whereby air may pass upward from said compartment through the coils 85 and downward into the other storage compartment.

5. The combination with a refrigerator having a vertical wall dividing the same into two storage compartments in communication at the bottom, the box having an aperture in the upper horizontal wall opening into the top of both compartments, of a refrigerating unit comprising a supporting member carrying the motor, compressor, etc., provided with a compartment for the expansion coils of the unit, said compartment being open at the bottom and registering with the opening in the refrigerator wall whereby air may ascend from one of the storage compartments through the expansion coil compartment and downward into the other storage compartment.

6. The combination with a refrigerator box having two storage compartments and an aperture in the upper horizontal wall 120

opening into the top of both storage compartments, of a refrigerating unit adapted to be attached to or removed bodily from the refrigerator box comprising a supporting member having a base fitting the refrigerator top and carrying the motor, compressor and circulating system including expansion coils, and being provided with a compartment open at the bottom only, the 5 opening of the compartment registering with the opening in the refrigerator wall, the expansion coils of the system being located in the said compartment of the unit, the expansion coil compartment having an inclined 10 wall on one side extending over the opening and the expansion coils being located nearer the opposite wall of the said coil compartment and directly over one of the storage compartments, the said inclined wall directing 15 ascending air about the expansion coils to fall by gravity into the other storage compartment.

7. The combination with a refrigerator box having an aperture in the upper horizontal wall, of a refrigerating unit adapted for attachment to or removal from the box comprising a base, a motor, a compressor and a circulating system including compression and expansion coils mounted on the base, a 20 compartment formed on the said base open at the bottom only through the base, the expansion coils of the circulating system only being carried in the said compartment, the opening of the compartment registering with 25 the opening in the refrigerator wall and the coils being disposed on one side of the coil compartment permitting air to rise into the coil compartment on one side and thence downward about the coils into the refrigerator. 30

8. In a refrigerating apparatus, the combination with a refrigerator having an opening or openings in its outside wall enclosing the space to be refrigerated, of a separate 35 and detachable cooling compartment located outside of the refrigerator and applied to said outside wall, said compartment communicating with said openings for permitting a circulation of air from the interior 40 space of the refrigerator to and from said cooling compartment, and a refrigerating

machine having its cooling element located within said outside compartment.

9. In a refrigerating apparatus, the combination with a refrigerator having an outside wall enclosing the space to be refrigerated, of a rigid frame or base mounted on the outside wall of the refrigerator, a cooling compartment outside of the refrigerator and carried by said base, a refrigerating 55 machine also carried by said base and having its cooling element located within said compartment, and means for permitting a circulation of air between the interior space of the refrigerator and said outside compartment. 60

10. In a refrigerating apparatus, the combination with a refrigerator having an opening or openings in its outside wall enclosing the space to be refrigerated, of a rigid frame 70 or base mounted on the outside wall around said opening or openings, a cooling compartment mounted on said base outside of the refrigerator and communicating with said opening or openings for permitting a circulation of air between the interior space 75 of the refrigerator and said compartment, and a refrigerating machine also carried by said base and having its cooling element located in said outside compartment. 80

11. A refrigerating unit adapted to be applied to an outside wall of a refrigerator, and comprising a rigid frame or base, a cooling compartment carried by said base and adapted to be supported outside of the refrigerator, and a refrigerating machine also carried by said base and having its cooling element in said compartment. 85

12. In a refrigerating apparatus, the combination with a refrigerator having an opening in an outside wall, of a separate cooling compartment located outside of the refrigerator over said opening and communicating therewith, a refrigerating machine having a cooling element located in said compartment, 90 and a deflecting plate extending from said compartment through the opening into the refrigerator for directing the air therefrom into said compartment. 95

In testimony whereof, I sign this specification. 100

CLARENCE M. HOLLEY.
